UNITED STATES PATENT OFFICE.

FREDERICK L. H. SIMS, OF TORONTO, ONTARIO, CANADA.

FOLDING BED.

Application filed December 8, 1921. Serial No. 520,986.

To all whom it may concern:

Be it known that I, FREDERICK L. H. SIMS, of the city of Toronto, in the county of York, Province of Ontario, Canada, a subject of the King of Great Britain, have invented certain new and useful Improvements in Folding Beds, of which the following is a specification.

This invention relates to beds which are 10 adapted to fold up to form a couch, and more particularly to that type in which the bed, when extended, has its ends parallel to the back of the couch, and my object is to devise a simple, strong and easily constructed bed, 15 which may be of full size when extended and which when folded will form a comfortable couch of normal proportions.

I attain my object by means of the constructions hereinafter described and illustrated in the accompanying drawings in which

Fig. 1 is a front elevation of my improved folding bed partly broken away and partly in section;

Fig. 2 a detail in end elevation, partly in section of parts of the bed illustrating more particularly the construction and mode of operation of the movable ends;

Fig. 3 an elevation of part of the same 30 showing more particularly the construction which enables the ends to be turned rearwardly;

Figs. 4 and 5 details illustrating the method of carrying the movable ends to enable them to be adjusted to different positions;

Fig. 6 a plan view of the bed partly in section and in the folded position;

Fig. 7 a vertical section of the extensible 40 frame carrying the mattress frame;

Fig. 8 a plan view partly broken away of parts of the same;

Fig. 9 an end elevation of the same parts;

Fig. 10 a side elevation of the bed partly 45 in section and with the near end removed, the mattress frame being shown in dotted lines in extended position;

Fig. 11 a front elevation of the spring head board;

Fig. 12 a front elevation, partly broken 50 away and partly in section, illustrating the arrangement of the foot board and the legs carried thereby;

Fig. 13 a sectional detail of the same parts 55 on a plane at right angles to Fig. 12; and

Fig. 14 a detail illustrating the method of

supporting the inner end of the mattress frame on the fixed end members when the bed is extended.

In the drawings like numerals of reference indicate corresponding parts in the different figures.

The main frame or housing of the bed comprises end members 1 of any suitable form and suitably cross connected as, for example, by the cross brace 2, and a back 3 supported from the end members by means of metal brackets 4, which are offset inwardly as shown to provide sufficient space at each end for the side members of the mattress frame hereinafter described. This back can easily be upholstered in any suitable manner.

The end members 1 are preferably provided with movable ends 5, which are adapted to assume either a vertical position as shown at the right hand side of Fig. 1, or a substantially horizontal position as shown at the left hand side of Fig. 1 with the surface which is then uppermost in substantial alignment with the upper surface of the seat 6 and which are supported as hereinafter described.

It is also desired that these ends shall be capable of being swung back out of the way by a vertical movement in a plane at right angles to the plane in which they normally stand. These movements are obtained by means of the following constructions. At the upper side of each fixed end member 1 is supported a carrying member 7. This carrying member is adapted to be swung rearwardly in a vertical plane to occupy a position substantially at right angles to that in which it normally lies. One method is to provide a hinged link 8 pivotally connected at one end to the top of the fixed member and at the other end to the under side of the carrying member 7. This link is normally received in a recess formed in the upper side of the fixed end member and is located adjacent the inner end of the carrying member, its position being such that the carrying member will either lie flat on top of the end member as shown in Figs. 1 and 2 of the drawings in full lines, or turned up on end as indicated in dotted lines in Fig. 2. The movable end may thus be swung back out of the way by turning up the carrying member.

To the carrying member the movable end 105 is connected by means of a pair of hinged

links 9 (see particularly Figs. 4 and 5). Each link is pivotally connected at one end to the carrying member 7 and at the other to the under side of the movable end. These 5 links are received in recesses formed in the carrying members and are so proportioned and positioned that the movable member may be brought to the position shown in full lines in Fig. 5 or swung down to the position 10 shown in dotted lines in the same figure, in either position resting flatly on the top of the fixed end member.

Under some circumstances it may be desirable to have the movable end member held 15 in an inclined position as shown in Fig. 4. This is readily effected by providing a shoulder 10 on the top of the carrying member against which the outer corner of the movable end member may engage as shown.

20 When the movable ends are in their normal vertical position it is desirable to lock them to the back 3 so that simple outward pressure against them will not displace them. For this purpose I provide at each end of the 25 back a projecting arm 11 having a notch formed therein with which a pin 12 extending rearwardly from the movable end may be engaged. To release the end it must be slightly lifted as it is swung outwardly. It 30 is desirable to lock the carrying members 7 down in place on the fixed ends when the bed is folded. For this purpose I secure to each carrying member a forwardly facing hook 48, which is adapted to be partly received in the notch 49 formed in the top of the fixed ends, thus resisting lateral displacement of the carrying member. A part 35 of the extension frame 18 is adapted to fit over the end of the hook 48, when the frame is pushed in to its limit, and thus the carrying members are firmly locked down and braced against strains tending to rock them transversely on the fixed ends, see Fig. 2.

45 The mattress frame in this bed comprises three sections 13, 14 and 15, the sides of which are hinged together at 16 and 17, the pivots or hinge pins being integral with the sides of the intermediate section 14 (see particularly Figs. 6, 7, 8, 9 and 10). This sectional mattress frame or truck is pivotally supported on an extension frame 18 which is slidable between the fixed ends 1 of the bed. This truck comprises a front and rearwardly extending members 19 secured to the front and preferably braced therefrom by the triangular plates 20. The rearward ends of these rearwardly extending members are connected by a cross bar 21 and rollers 60 22 are suitably connected with the front of the extension frame and the cross bar 21 to facilitate the extension of the frame to the position shown in dotted lines in Fig. 10. The front of the frame supports the U-shaped metal member 23, the upper ends of

which are slightly offset rearwardly and are pivotally connected with the mattress frame by the same pivots 16 which form the hinges between the outer section 13 of the mattress frame and the intermediate section 14. 70 When the bed is folded and the truck pushed into position between the end members 1 as shown in full lines in Fig. 10 the inner section 15 of the mattress frame rests upon the cross bar 21 connecting the rearwardly extending members 19 of the truck. The intermediate member 14 then occupies a substantially vertical position below the pivot 16, while the outer member of the mattress frame lies in a substantially horizontal position behind the pivot 16. When in this position, this part of the mattress frame is supported by means of the folded mattress employed with the bed, the head rest herein-after described and finally, if the frame section is sufficiently depressed by the rule joints at the pivots 16 also hereinafter referred to:

Laterally extending pins 24 are provided 90 on the sides of the inner section of the mattress frame and blocks 25 or other supports are connected with the inner sides of the fixed ends 1 of the bed frame on which the pins 24 rest when the bed is extended and the inner section is in the position shown in dotted lines in Fig. 9.

Over the rearward blocks 25 are supported the keepers 26 which serve to prevent the inner part of the mattress frame being tilted upwardly when the bed is in use. These blocks 25 are preferably formed of metal plates offset to space their upper edges from the main frame, while the pins 24 adjacent the intermediate section of the mattress frame are formed with lips overhanging the upper edges of the blocks so that they cannot slip off if any strains are exerted tending to spring apart the sides of the main frame. The rearward pins may be similarly formed though the need is materially less, as the rear part of the frame is tied by the back 3. 100

The mattress frame is formed of metal angle bars of T-section, with preferably a slight variation in the case of the intermediate section, the stems of the angle bars being inwardly directed and having the flexible metallic mattress fabric 31, which may be of any ordinary construction, secured thereto by means of the usual tension springs. The flanges of the ends of the outer sections are formed integral with the flanges of the sides of the adjacent section, but the stems are divided, overlapped and secured together, thus forming a strong, rigid corner. The pivots 16 and 17 are in alignment with the stems of the T-sections, as shown particularly in Figs. 7, 9 and 10 of the drawings. With this arrangement 110 the strain exerted by the springs of the 120

metallic mattress fabric acts in the same plane or planes as the axes of the pivots whether the bed is open or closed or in any intermediate position, and the pull being thus always in the planes of the stems of the **T**-sections, the twisting effect on the mattress frame which exists with **L**-shaped sections is avoided.

I am further enabled, as will be seen particularly on reference to Figs. 7 and 9, to make the pivots of ample size without unduly weakening the side members of the frame, and I am further enabled to secure rule joints between the sections of much greater strength than has been heretofore possible. At the joints, it will be noted, the stems of the **T**-sections of the mattress frame sections 13 and 15 are cut away to make room for the pivots and that the shoulders 27 formed on the sides of the intermediate mattress section and which is adapted to engage the stem of the adjacent **T**-angle member is sufficiently distant from the centre of the pivot to give it an effective bearing against the stem and thus make a strong joint when the sections are in alinement.

The flanges of the sides of the intermediate section are also preferably cut away to form the shoulders 28 which engage the stems of the adjacent **T**-angles when the bed is folded. It will be noted that the stem of the **T** at each end of the sides of the intermediate mattress frame section extends past the pivot, which it may do since the pivot is integral with the side, sufficiently far to meet the stem of the sides of the adjacent sections when the mattress frame is extended. I can thus secure my mattress fabric to the sides of the mattress frame sections exactly in line with the pivots, which eliminates objectionable bulging of the fabric when the mattress frame is folded. The side members of the intermediate section of the mattress frame are also preferably formed with a greater thickness of material in the flange than the **T**-sections of which the other parts of the mattress frame are formed, thus further increasing the strength of the joints and giving the shoulders 27 and 28 a wide bearing on the stems of the adjacent **T**-sections. In this intermediate section the exact **T**-form is departed from, the **T**-form being found at the ends only, while the center is of **L**-section. The two forms of section merge into one another gradually one leg of the **L**-section being integral with and also in alinement with the stems of the **T**-sections. The other leg of the **L**-section is deepened to maintain the stiffness and strength of the member.

By this construction the pivots 16 may be brought closer to the front than is otherwise possible without interference between the side members of the section and the horns of the **U**-shaped member 23. This means that

the depth of the bed from back to front when folded, and particularly the overhang and width of the seat may be somewhat reduced which is a desideratum.

The operation of extending and folding the bed is substantially as follows. The movable ends 5 are swung out of the way and the truck is then pulled forward, usually by placing the hands on the seat 6 which is connected with the mattress frame as hereinafter described, and exerting a forward pressure. The truck slides forward between the fixed ends and this movement is continued until the keeper 29 secured to the cross bar 21 of the truck engages beneath the cross brace 2 of the main frame. The lifting handle is thus exposed and is pulled upon and the outer section 13 of the mattress frame is thus swung upwardly until it is alined in a vertical position with the intermediate section 14. The rule joints of the pivots 16 then prevent further relative movement between the outer and intermediate sections. The movement of the outer section is continued and the intermediate section then swings on the pivots 7. The inner section swings on the pivots 7 until the further relative movement of the two sections is prevented by the rule joints of the pivots 17. The movement of the outer section is still continued and the inner and intermediate sections are thus swung up to a horizontal position with the pins 24 on the inner section in front of the blocks 25. The mattress frame is then pushed rearwardly until the pins or projections 24 thereon engage over the rearward blocks 25 and under the keepers 26. The inner end of the mattress frame is then firmly supported in the horizontal position.

The outer end of the outer section is supported by suitable legs. In the arrangement shown these legs are carried by the arms 33 on which the foot board 32 is carried, these arms 33 being hinged at each side of the section on the blocks 34 secured to the mattress frame. A cross bar 35 preferably connects these brackets forming a fixed foot board. The legs 36 are hinged on the arms 33 so as to swing transversely of the bed. When the bed is being folded the foot board is hinged down to engage and hold the mattress employed with the bed and when the foot board is in this position the legs are swung up and extend longitudinally of the bed and may thereafter move or be moved to extend transversely of the bed. When the bed is extended and the movable foot board is raised to the vertical position, the legs swing inwardly by gravity until restrained by the stops 37 carried by the legs which engage the arms 33 which carry the fixed foot board. It is desirable that the foot board be frictionally held in its folded down position so that it retains its grip on the

mattress and bed clothes, as the bed is folded. For this purpose I stamp a tit 46 on each arm 33, which is adapted to spring into a recess 47 formed in the corresponding bracket 34 when the foot board is folded down and which will spring out again when a moderate degree of force is applied to swing the foot board up again.

The bed is provided with a headboard 10 which comprises an elliptic spring 38 supporting a transverse member 39. These parts are preferably so proportioned that when the bed is folded, the cross transverse member 39 engages the fixed part of the 15 foot board and compresses the elliptical spring 38 so that when the extension frame is pulled forward, the spring 38 tends to lift the inner end of the outer section of the mattress frame, thus facilitating the 20 opening of the bed.

The great strain of the tension springs of the mattress fabric 31 necessitates the provision of a cross brace adjacent the point of connection of the inner and intermediate 25 mattress frame sections, but this brace must, when the bed is in use, be well below the plane of the mattress fabric to allow for the sag which necessarily takes place when weight is put on the mattress and, when the bed is 30 folded, the brace must lie in the very small space between the under side of the mattress frame section and the floor. I therefore employ a U-shaped brace 40, the ends of which are pivoted at 41 on the sides of the inner 35 section 15 of the mattress frame. To ensure this brace folding up when the bed is folded I connect thereto one end of a coil spring 42, the other end of which is connected with the end of the mattress frame 40 section 15. This spring tends to maintain the brace parallel to the under side of the mattress fabric, while it is sufficiently elastic to permit the brace to swing down readily when weight is placed on the fabric 31.

Owing to the sag which takes place in the mattress fabric 31 when weight is placed upon it as hereinbefore referred to, it is impossible to employ a continuous solid front for the extension frame 18, and a gap 50 must be provided at the upper side of the front, which in the ordinary type of divanette, is usually filled with a piece of flexible fabric. This construction I find undesirable, and I employ in lieu thereof a front board 43 hinged at its lower edge to the fixed part of the front of the extension frame. This front, when the bed is folded, is held in a vertical position by a chain 44 secured to the front and to the outer section 55 of the mattress frame. When this outer section is swung outwardly, the chain is slackened and the hinged front allowed to fall. Its fall, however, will not take place until the seat has dropped to the position 60 shown in dotted lines in Fig. 10. The seat

is connected with the outer section of the mattress frame to hinge down so that it does not in any way interfere with the sagging of the mattress fabric 31 when weight is placed thereon. When the bed is folded 70 the seat falls naturally to the position shown in full lines in Fig. 10.

The method of extending the bed has been hereinbefore described and, when the bed is so extended, as the movable ends 5 have 75 been swung outwardly and then rearwardly as hereinbefore described to bring them substantially parallel to the wall, the sides of the bed are left open and unobstructed as in an ordinary bed. The bed is folded by 80 reversing the process of extension.

A folding bed constructed substantially as described possesses the following advantages. The device may be used as an ordinary sofa when the movable ends are in their 85 normal vertical position, and when so used is scarcely distinguishable from an ordinary sofa owing to the close fit between the seat and the back and ends. At the same time if anyone desires to use the sofa to recline 90 upon, one or both movable ends may be dropped to the horizontal position. When the device is used as a bed these ends will usually be required to be swung back entirely 95 out of the way as their fit is so close to the 25 seat as to prevent the pulling out of the extension frame.

Owing to the specific construction of the mattress frame of T-angle bars with the fabric lying in the same horizontal plane 100 with the axes of the joints when the bed is open, and in three planes at right angles to one another when the bed is closed, the tendency of the frame to "wind" or twist when opening or closing is practically eliminated. As the mattress frame is formed of three sections only, with its major sections similar, the cost of the frame is kept down to a minimum. The mattress frame, being supported on an extension frame which is 105 readily disconnectable from the main frame, the handling of the device is greatly facilitated either for shipping or storing or for installation in the apartment in which it is to be used. With the present construction 110 no springs are employed which are essential to the opening and shutting of the bed. The device is compact so that I am able to keep the seat low and not too deep from back to front, and the bed when extended fairly 115 high. I am also enabled to employ a fixed back which does not require to be moved or interfered with in the operation of the bed. The back being fixed, the whole of the 120 main frame or housing may be made substantial and rigid.

What I claim as my invention is:—

1. In a folding bed, the combination of a housing and a truck slidably relative to the housing; a mattress frame pivotally con- 130

5 nected intermediate of its ends to the forward part of the truck and formed in three sections hinged to one another; projections on the inner mattress frame section; and supports on the rearward part of the housing adapted to support the inner section of the mattress frame when the bed is extended and the truck pushed in to bring the projections over the supports.

10 2. In a folding bed, the combination of a housing and a truck slideable relative to the housing; a mattress frame pivotally connected intermediate of its ends to the forward part of the truck and formed in three sections hinged to one another by rule joints; legs carried by the outer mattress frame section adapted to rest on the floor when the bed is extended; projections on the inner mattress frame section; and supports on the housing adapted to be engaged by said projections to support the inner section of the mattress frame when the bed is extended and the truck pushed in to bring the projections over the supports.

15 3. In a folding bed, the combination of a housing and a truck slideable relative to the housing; a mattress frame pivotally connected intermediate of its ends to the forward part of the truck and formed in three sections hinged to one another by rule joints; legs carried by the outer mattress frame section adapted to rest on the floor when the bed is extended; projections on the inner mattress frame section; supports on the housing adapted to be engaged by said projections to support the inner section of the mattress frame when the bed is extended and the truck pushed in to bring the projections over the supports; and keepers over said supports preventing upward movement of said projections.

20 4. In a folding bed, a sectional mattress frame having its sides formed substantially of T angle bars similarly arranged in each section, the flanges of the sides of the sections being pivoted together by pivots positioned in alinement with the stems of the T's, said stems being cut away adjacent to the pivots, a shoulder being formed on the flange of the side of a section at each joint adapted to engage the stem of the side of the adjacent section to form a rule joint.

25 5. In a folding bed, a sectional mattress frame having its sides formed substantially of T angle bars similarly arranged in each section, the flanges of the sides of the sections being pivoted together by pivots positioned in alinement with the stems of the T's, the stem of the side of one section at each joint being cut away to clear the adjacent pivot and the stem of the side of the adjacent section extending past the axis of the pivot to substantially contact with the first mentioned stem when the sections are

30 6. A sectional mattress frame constructed substantially as set forth in claim 6 in which the pivots are integral with the sides of the section in which the stems of the T's overlap the pivots and the overlapping parts of the stems are also integral with the sides.

35 7. In a folding bed, a sectional mattress frame having its sides formed substantially of T angle bars similarly arranged in each section, the flanges of the sides of the sections being pivoted together by pivots positioned in alinement with the stems of the T's, the stem of the side of one section at each joint being cut away to clear the adjacent pivot, and the flange of the side of the adjacent section being formed with spaced shoulders adapted to engage opposite sides of the stem aforesaid to limit the swing of the sections upon one another in either direction.

40 8. In a folding bed, the combination of a main frame formed of two parts slidably connected, the forward part including a U-shaped member with upwardly extending arms; a mattress frame pivotally connected, intermediate of its ends, to the ends of the U-shaped member and formed in three sections hinged to one another; a bent cross brace pivotally connected at its ends to the sides of the inner section adjacent its point of connection with the intermediate section; and spring means connected to said brace and to the mattress frame tending to draw the brace to a position parallel to the mattress frame.

45 9. In a folding bed, the combination of a supporting frame; a folding mattress frame carried thereby; a bent cross brace pivotally connected at its ends to opposite sides of the mattress frame; and a coil spring connected to said brace and to the mattress frame tending to draw the brace to a position parallel to the mattress frame.

50 10. In a folding bed, the combination of a U-shaped supporting member with upwardly extending arms and a mattress frame formed in three sections hinged to one another and pivotally connected with the arms aforesaid by means of pivots substantially co-axial with the hinge joints between two of the mattress frame sections, the end sections having their sides formed of T-angle bars, each side of the middle section being formed of T-section while in its middle portion the head of the T is displaced in a direction away from the transverse part of the U-shaped member, whereby said transverse part may contact with the sides of the middle sections approximately in a plane intersecting the pivots between the sides of the section.

55 11. In a folding bed; a frame; a fixed end member on the frame; an extension frame movable in a direction parallel to the said end member; a movable end; a carrying

120

125

130

135

member for the movable end so connected to the fixed end that it is swingable thereon in a vertical plane; a hook secured to the underside of said carrying member; and a part 5 on the extension frame engageable with the hook when the extension frame is pushed in to hold down the said carrying member.

12. In a folding bed; a frame; a fixed end member on the frame; an extension 10 frame movable in a direction parallel to the said end member; a movable end; a carrying member for the movable end so connected to the fixed end that it is swingable thereon in a vertical plane; a hook secured to the 15 underside of said carrying member; and a part on the extension frame engageable with the hook when the extension frame is pushed into hold down the said carrying member, a notch being formed in the fixed end to partly 20 receive the hook.

13. In a folding bed, the combination of a housing provided with fixed ends; a truck 25 slideable into and out of the housing; a seat supported on the truck and extending above the fixed ends when the truck is positioned within the housing; movable end members for the housing; and hinged connections for

said movable end members proportioned to enable each of the movable end members to be swung to lie with either of two adjacent 30 sides parallel to the top of the corresponding fixed end member and the other of said sides pressed against the end of the seat.

14. In a folding bed, the combination of a housing provided with fixed ends; a truck 35 slideable into and out of the housing; a seat supported on the truck and extending above the fixed ends when the truck is positioned within the housing; carrying members for movable end members each supported on one 40 of the fixed end members so that it may lie horizontally thereon or be swung back to a vertical position; movable end members for said housing; and hinged connections between the movable end members and the 45 carrying members proportioned to enable each of the movable end members to be swung to lie with either of two adjacent sides resting on the corresponding carrying member and the other of said sides pressed 50 against the end of the seat.

Signed at Toronto, Canada, this 24th day of November, 1921.

FREDERICK L. H. SIMS.
